Des. 179,111
Patented Nov. 6, 1956

179,111

TELEVISION ANTENNA

Alex M. Ballan, Wawarsing, Albert Sokol, Ellenville, and Thomas Arlen Richmond, Middletown, N. Y., assignors to Channel Master Corporation, Ellenville, N. Y., a corporation of New York

Application May 17, 1956, Serial No. 41,523

Term of patent 14 years

(Cl. D26—14)

Fig. 1 is a front perspective view of a television antenna embodying our new design;
Fig. 2 is a top plan view thereof;
Fig. 3 is a front elevation; and
Fig. 4 is a side elevation view thereof.

We claim:
The ornamental design for a television antenna, as shown.
